By his Attorney,
Kelson M. Farland

UNITED STATES PATENT OFFICE.

HOMER B. MILLER, OF GARDINER, MAINE, ASSIGNOR TO UNITED SHOE MACHINERY CORPORATION, OF PATERSON, NEW JERSEY, A CORPORATION OF NEW JERSEY.

EYELETING MACHINE.

Application filed August 26, 1918, Serial No. 251,456. Renewed March 31, 1921. Serial No. 457,424.

To all whom it may concern:

Be it known that I, HOMER B. MILLER, a citizen of the United States, residing in Gardiner, in the county of Kennebec and State of Maine, have invented certain Improvements in Eyeletting Machines, of which the following description, in connection with the accompanying drawings, is a specification, like reference characters on the drawings indicating like parts in the several figures.

This invention relates to eyeletting machines and is herein shown as embodied in a machine particularly designed for setting invisible or blind eyelets. It will be understood, however, that the invention is applicable to other types of machines and may be used for purposes other than the ones herein emphasized.

In setting invisible eyelets, a combined punching and setting tool is being extensively used which tool is provided with an intermediate projecting shoulder adapted to be located between the layers of the work and to serve as an upsetting surface for an eyelet presented thereagainst so as to clinch the same over only a portion of the layers of the work. This setting tool may be conveniently used, for example, in the type of machine illustrated in Letters Patent of the

United States No. 1,205,277, granted November 21, 1916, upon an application of Walter Shaw, and the present invention has been illustrated in connection with such a ma-

chine. In the operation of a machine of this type, the combined punching and setting tool is forced through the layers of the work against a suitable punching surface and the tool is then moved laterally to feed the work for a predetermined distance and to bring the perforation into alignment with the eyelet presenting tool normally disposed below the work support. The eyelet presenting tool is then elevated to pass the eyelet

through the previously formed perforation and to upset it against the upsetting surface of the combined tool. When the machine is used for setting invisible or blind eyelets and a tool of the type described is utilized, some difficulty has been experienced because of the tendency of the work to be forced off the tapered portion of the combined punching and setting tool and further because the eyelet has been relied upon to force the upper layer of the work, in which the eye-

let is not to be set, above the upsetting shoulder of the tool.

One object of the invention is to provide improved means for advancing the work along the punch after the latter has punched a hole but before the setting tools begin to cooperate with each other to set an eyelet in the work. This improvement, when utilized for the invisible eyeletting, preferably advances the work far enough to force at least one layer of the work beyond the upsetting shoulder of a combined punching and upsetting tool.

Another object of the invention is to accomplish the advancing of the work along the punch otherwise than by moving the plate or block with which the punch coacts to form the hole, so that the plate or block may, if preferred, be fixed to insure the maximum accuracy of cooperation with the punch.

A feature of the invention consists in the combination with a punching-and-setting tool, of a fixed punch-block with which the tool coacts to punch and to feed the work, and means movable relatively to the punch-block for advancing the work along the punch after the latter has formed the hole in the work, but before the eyelet is inserted in the work.

Other features will become apparent upon a consideration of the following specification taken in connection with the accompanying drawing, in which,—

Fig. 1 is an angular view of the front end of an eyeletting machine, and

Figs. 2 and 3 are views, partly in section, of the operating tools showing the position of the parts during the punching and the setting operations respectively.

Reference is made to the above-mentioned patent for a description of parts of the machine not herein specifically illustrated and described. It will be understood, however, that such a machine comprises a frame 10 in which there is mounted a power operated shaft 12. Mounted for reciprocation in the frame and controlled by a cam 14 upon the shaft 12 is an eyelet presenting tool 16 provided with a spindle 18. Eyelets are supplied to this spindle from a raceway 20 in the usual fashion, the raceway being retracted prior to the presentation of the eyelet to the work. Co-operating with this eyelet presenting tool is a combined punching 110

and upsetting tool 22 carried in a lever 24 which is suitably connected to the power shaft 12 so as to cause the tool to perforate the work, move the same laterally to bring the perforation into alignment with the tool 16, to withdraw the tool from the work, and return the same to a predetermined initial position for a subsequent operation.

It will be noted that the particular form 10 of combined tool 22 herein illustrated is provided with a tubular punching member 26 at its extremity and with an upsetting shoulder 28 adapted to be located between the layers of the work and hence to upset 15 the barrel of an eyelet over only a portion of said layers. A punch block 30 is mounted in the frame of the machine and is arranged for the purpose of supporting the work during the punching operation.

Surrounding this punch block is a work 20 supporting table 32 which is provided with a suitable aperture 34 for the admission of the eyelet presenting tool 16. According to the preferred embodiment this work supporting 25 table is mounted upon rods 36 and 38 passing through bearing apertures in the frame of the machine and connected at their lower ends by a cross bar 40. Springs 42 are interposed between the frame of the machine and the cross bar to hold the work 30 supporting table in its lowermost position with its upper surface substantially at the level of the surface of the punch block. The cross bar 40 is provided with a suitable bearing 35 surface arranged to rest upon the peripheral surface of the cam 14 and said cam is provided with a projecting hump 44 designed to elevate the work supporting table 32 at a predetermined point in the operation 40 of the machine so as to urge the work toward the upsetting shoulder 28 of the combined tool 22 and tending to force a portion of the layers thereof over the upsetting shoulder.

Preferably the operation of the machine 45 will be such that the combined tool 22 is depressed against the work over the punch block 30 at a predetermined initial point so as to perforate the work. The downward pressure of the combined tool is then relieved slightly and this tool is then moved laterally to feed the work and to bring the perforation into alignment with the eyelet presenting tool 16. During this operation the spindle 18 will have been passed through 50 the endmost eyelet in the raceway 20 and the raceway will have been retracted to carry it out of alignment with the operating tools. When the previously formed perforation has been brought into alignment with the eyelet 55 presenting tool at a predetermined time with respect to the movement of the latter, the work supporting table will be positively lifted by the raised hump 44 upon the cam 14 after which the eyelet presenting tool will 60 force the eyelet through a portion of the

layers of the work and cause it to be upset against the shoulder 28 of the upper tool. Continued rotation of the power operated shaft will cause the separation of the co-operating tools and depression of the work 70 supporting table under the impulse of the springs 42 and the return of the combined tool to its initial punching position ready for a repetition of the operation.

What I claim is:

1. In an eyeleting machine, an eyelet-presenting tool, a clenching die arranged to cooperate therewith, a punching member associated with the clenching die, and means movable relatively to the punching member in a direction such as to force the punched work along the punching member toward the clenching die prior to the presentation of the eyelet by said presenting tool.

2. In an eyeleting machine, a combined punching and upsetting tool, a punch-plate arranged to cooperate with the punching element of said tool, a co-operating eyelet presenting die, means for relatively operating said tool and die to set an eyelet, and movable means other than said punch-plate, constructed and arranged to force the work positively on to the combined tool prior to the presentation of an eyelet against the upsetting die.

3. In an eyeleting machine, two cooperative eyelet-setting tools one of which has a work-feeding portion and is movable to feed the work, and work-engaging means movable toward the setting portion of said feeding tool to urge the work along said feeding portion toward the setting portion.

4. In an eyeleting machine, a punching and setting tool constructed and arranged to feed the work, an eyelet setting tool arranged to cooperate therewith, and movable means constructed and arranged to move toward the first said tool to move the work relatively thereto at a predetermined time with respect to the movements of one of said tools.

5. In an eyeleting machine, a tool for feeding the work and clenching an eyelet, an eyelet inserting tool, and power operated means constructed and arranged to urge the work toward the first said tool.

6. In an eyeleting machine, a combined punching and setting tool, a co-operating eyelet presenting tool, means for causing said combined tool to perforate the work at 120 a point out of alignment with the eyelet presenting tool and move the work laterally to bring the perforation into alignment with the eyelet presenting tool, and work-engaging means movable in a direction such 125 as to force the work along the punching portion of the combined tool before the barrel of an eyelet is clinched upon the upsetting surface.

7. In a machine for setting invisible eye-

lets, a combined punching and upsetting tool constructed and arranged to perforate a plurality of layers of work and provided with an upsetting shoulder adapted to 5 be located between the layers of the work, a co-operating eyelet presenting tool, movable work-engaging means for forcing the work along the combined punching and upsetting tool, and means for moving the first 10 said means so as to force a layer of the work past said shoulder.

8. In an eyeleting machine, a combined punching and setting tool, a co-operating eyelet presenting tool, a punch block arranged to coact with the first said tool, work 15 supporting means, and means for positively moving said work supporting means relatively to the punch-block to urge the work toward the combined tool.

9. In an eyeleting machine, eyelet-setting mechanism comprising cooperative setting tools one of which has a punch, a punch-block arranged to cooperate with the punch 20 to form a hole in the work, means for actuating the punching tool to feed the work, and work-engaging means movable relatively to the punch-block in a direction such as to advance the work along the punch toward 25 the setting shoulder of the punching tool.

10. In an eyeleting machine, eyelet-setting mechanism comprising cooperative setting tools one of which has a punch, a fixed punch-block arranged to cooperate with the punch, means for moving the 30 punching tool laterally beyond the area of the punch-block to feed the work, and work-engaging means constructed and arranged to advance the work along the punch after the feeding operation and prior to cooperation 35 of the setting tools.

11. In an eyeleting machine, a setting tool having a punch, mechanism arranged to im-

part punching and feeding movements thereto, a punch-block constructed and arranged to cooperate with said tool to form 45 a hole in the work and to keep the work on the punch during the feeding movement of the latter a tool arranged to cooperate with the first said tool after the feeding operation to set an eyelet, and means arranged to advance the work along the punch after the feeding movement and prior to cooperation 50 of the setting tools.

12. In an eyeleting machine, eyelet-setting mechanism comprising cooperative setting tools one of which has a punch, a fixed punch-block, the punching tool being arranged to cooperate alternately with the punch-block and with the other setting tool and to feed the work along the punch-block, 60 a movable work-support, and means arranged to move the work-support after the feeding operation and prior to the setting operation in a direction such as to advance 65 the work along the punch.

13. In a machine for setting eyelets in one or more layers of a plurality of superposed layers of work, a punching tool having an eyelet-upsetting shoulder adapted to enter the punched hole, means arranged to 70 cooperate with said tool to punch a hole, means arranged to separate the tool and the first said means, means arranged to advance the work along said tool so as to insert the shoulder into the punched hole, and means 75 arranged to cooperate with said tool to set an eyelet against the inserted shoulder.

In testimony whereof I have signed my name to this specification.

HOMER B. MILLER.
